DESIGN FOR A CONTAINER FOR PERFUME OR THE LIKE

Abraham Levy, New York, N. Y.

Application November 5, 1940, Serial No. 96,327

Term of patent 3½ years

To all whom it may concern:

Be it known that I, Abraham Levy, a citizen of the United States and a resident of the city and State of New York, with a post office address at No. 6 East 39th Street, in the Borough of Manhattan, city and State of New York, have invented a new, original, and ornamental Design for a Container for Perfume or the like, of which the following is a specification, reference being had to the accompanying drawing, forming part thereof, in which

I claim:

The ornamental design for a container for perfume or the like, as shown.

ABRAHAM LEVY.
